US0D1058357S

(12) **United States Design Patent** (10) **Patent No.:** **US D1,058,357 S**
(45) **Date of Patent:** **** Jan. 21, 2025**

(54) **PLASTIC GUIDE RAIL**

(71) Applicant: **Changzhou Joshua Home Furnishing Co., Ltd.**, Changzhou (CN)

(72) Inventor: **Yantao Liu**, Changzhou (CN)

(73) Assignee: **Changzhou Joshua Home Furnishing Co., Ltd.**, Changzhou (CN)

(**) Term: **15 Years**

(21) Appl. No.: **29/947,929**

(22) Filed: **Jun. 18, 2024**

(51) LOC (15) Cl. **08-05**

(52) U.S. Cl.

USPC **D8/381**

(58) **Field of Classification Search**

USPC D8/381, 377, 374, 350, 363, 364, 366
CPC A47B 88/73; A47B 88/477; A47B 88/423;

A47B 96/027; A47B 96/061
